CLAIM

The ornamental design for a medical imaging device as shown and described.

DESCRIPTION

FIG. 1 is a front view of a medical imaging device showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a top, front, right-side perspective view thereof;

FIG. 8 is an enlarged partial view of FIG. 7 showing the front opening of the bore; and,

FIG. 9 is an enlarged partial view of FIG. 2 showing the rear opening of the bore.

The broken lines immediately adjacent to the shaded area define the bounds of the claimed design and form no part thereof. The unshaded areas and broken lines depicting the remainder of the medical imaging device form no part of the claimed design. The dot-dash broken lines in FIGS. 8 and 9 represent the boundaries of the respective enlarged partial views and form no part of the claimed design.
